(57) **CLAIM**

The ornamental design for lighthouse play structure, as shown and described.

DESCRIPTION

FIG. 1 is a perspective view of a lighthouse play structure showing my new design;

FIG. 2 is a front view thereof;

FIG. 3 is a rear view thereof;

FIG. 4 is a top plan view thereof; and,

FIG. 5 is a left side view thereof.

The right side view is identical to the left side view and the bottom of the lighthouse play structure is flat and unornamented.
